UNITED STATES PATENT OFFICE.

LAWSON H. GIDDINGS, OF PASADENA, CALIFORNIA.

ELECTRIC FURNACE.

Application filed March 15, 1926. Serial No. 94,759.

This invention relates to electric furnaces, and refers particularly to a furnace for use in cremation of bodies.

An object of the present invention is to provide a practical electrical heating furnace which is adapted to operate at high temperatures in the presence of an oxidizing gas.

More particularly, the object of the present invention is to provide an electric furnace which is adapted for cremation purposes.

A feature of the present invention resides in the employment of a novel means for passing air or other gas over the ends of electric resistance rods of the furnace, whereby both to heat such air or gas and to maintain the terminals of the rods cool.

The present invention also provides a means by which all of the air and gas or substantially all of the air and gas is caused to be positively directed against or across the electrical heating elements in finding its way into the furnace, together with means by which the heated air or gas is caused to be positively directed against the object to be heated.

Various further objects, advantages and features of the present invention will be understood from the following description of a preferred form or example of a furnace embodying the invention. For this purpose, reference is made to the accompanying drawings in which a type of furnace is illustrated particularly adapted for the cremation of bodies.

In the drawings:

Figure 1 is an elevation in section of the furnace,

Figure 2 is a section on line 2—2 of Figure 1, and,

Figure 3 is an enlarged fragmentary sectional view of the resistor rods employed for heating the furnace.

Referring to the drawings, the furnace consists of a structure of bricks or other fire and heat resisting material having a top wall 2 and side walls 3 of sufficient thickness to serve to retain the heat in the furnace.

Within the furnace and preferably extend-

ing therethrough from end to end, is a chamber or retort 4 for the reception of the object to be heated. The retort chamber is provided at its front and rear ends respectively with doors 5 and 6, which are provided with suitable means so they can be opened, as desired. The retort chamber 4 is provided with a floor 7 which is preferably aslant upwardly from the front to the rear end of the retort chamber. At the rear of the retort chamber, there is provided an exit flue 8 for the gases from the chamber 4, said flue preferably extending downwardly as indicated in Figure 1. The floor 7 of the retort chamber is preferably provided with a central trough 9 for collection of ashes and with two side troughs 10 and 11 which operate when the furnace is employed for cremation purposes to collect the metal from the handles of the casket.

At the front end of the retort chamber, there is a narrow longitudinal opening 12 in the floor 7, at the bottom of the central trough 9, which opening 12 establishes communication between the forward part of the retort chamber 4 and a lower chamber 13 in which are disposed the heating elements or resistor rods of the furnace. Said lower chamber 13 is formed by two longitudinal side walls 14 and 15, together with the rear end wall 16 and forward end wall 17. The bottom of the lower chamber is preferably provided with a perforated floor 18 below which there is a passage 19 leading to the front end of the furnace, as shown at 20.

Along the top portion of the gas heating chamber 13 there is supported a tray 21 below the longitudinal opening 12 to receive the ashes, said tray 21 being of narrower width than the width of the chamber 13 and 90 being supported by the cross members 22.

The lower portion of the heating chamber 13 is provided with electrical resistor rods 23 which are indicated as preferably disposed in two vertically spaced apart rows, 95 each row extending throughout the length of the heating chamber 13. These resistor rods 23 are indicated as provided with connecting rods 24 extending through the side walls 14 and 15 of the heating chamber 13. 100

These connecting rods should be of a material adapted to withstand considerable heat and may, for example, be formed of chromium steel. The side walls 14 and 15 are 5 provided with openings 25 of substantially larger diameter than the diameter of the connecting rods 24 so that said openings may accommodate protecting tubes 26 while still leaving an annular opening 27 between the 10 connector rods 24 and said tubes 26 whereby air or other gases may be passed into the fire chamber 13 longitudinally through said openings 27 along the connector rods 24 and across the ends of the resistor rods 23. By 15 this construction, the resistor rods 23 and their connecting rods 24 are merely suspended within the openings in the side walls 14 and 15 and within the chamber 13. In order to provide for such suspension, I pro- 20 vide spring butt end terminal members 28 at the end of each resistor and its connecting rods, which terminals in turn are secured to castings 29 properly mounted on or attached to the side walls 14 and 15, being preferably 25 spaced therefrom by insulation 30. 31 indicates a receptacle into which the ashes from the tray 21 may be raked.

In operation, the object to be heated is placed on the floor 7 of the retort chamber 4. 30 For example, when the furnace is employed in cremation purposes, the casket carrying the body is placed in the retort chamber by removing the rear end door 6. Thereupon current is supplied to the resistor rods 23 to 35 heat air or other gases which are caused to flow into the heating chamber 13 across the ends of the resistor rods 23 accomplishing a very important result in preventing the ends of such resistor rods from being burned out, 40 at the same time, supplying gas for the furnace. If desired, all of the gas or air for the furnace may be supplied through these openings leading along the ends of the resistor rods 23. At other times, it may be 45 preferable to admit or force further air through the opening 20 and passage 19 up transversely across the resistor rods 23. The gas supplied to the furnace may be entirely 50 pure air, in which case it will have the most efficient oxidizing action, or at other times, it may be preferable to admit into part of the furnace, flue gas having a lower oxidizing content, the character of gases being widely 55 variable. The gases heated within the heating chamber 13 passes upwardly through the longitudinal slot 12, thereby being positively directed against the casket or other object placed directly thereover, so that the heat of these gases is most efficiently placed upon 60 the object. At the rear end of the retort chamber, further air may be admitted to complete the combustion, although this is not entirely essential to the operation of the furnace. 65 It is understood that I do not limit the

present invention to the particular construction shown in the drawings for the purpose of illustrating the invention, nor necessarily in all of the claims to its use as a cremation furnace, but the invention includes all such 70 changes in construction as may be made without departing from the spirit of the invention, and the invention is of the scope set forth in the appended claims.

I claim:

1. In a furnace of the class described, a furnace chamber, a plurality of electrical resistor rods for heating gases for said chamber, means for passing said gases endwise along the terminal ends of said resistor rods 80 as they flow to said furnace chamber, and means for directing the gases which pass into said furnace chamber against the object to be heated.

2. In a furnace of the class described, a furnace chamber, a floor for said chamber, a heated chamber below said floor, said floor being provided with a narrow longitudinal opening connecting the furnace chamber and heating chamber, electrical resistor rods in 90 said heating chamber, and means for passing gases longitudinally inwardly along the ends of the resistor rods in entering said heating chamber.

3. In a furnace of the class described, a furnace chamber, a floor for said chamber, a heating chamber below said floor, said floor being provided with a narrow longitudinal opening connecting the furnace chamber and heating chamber, electrical resistor rods in 100 said heating chamber, means for passing gases longitudinally inwardly along the ends of the resistor rods in entering said heating chamber, and means for passing other gases upwardly transverse to said resistor rods 105 in entering said heating chamber.

4. In means of the class described, a chamber provided with a plurality of resistor rods, side walls for said chamber having openings through which said resistor rods extend, the 110 openings providing an annular space around the ends of said resistor rods for the passage of gas into said chamber.

5. In means of the class described, a chamber provided with a plurality of resistor rods, side walls for said chamber having openings through which said resistor rods extend, the openings providing an annular space around the ends of said resistor rods for the passage of gas into said chamber, a 115 perforated floor for said chamber, and means for passing gases through said perforated floor and transverse to said resistor rods in 120 entering said chamber.

6. A crematory furnace comprising a retort chamber, an ash collecting trough in the floor of said chamber, an opening in the lower end of said trough, a collecting tray below said trough, means for passing heated gases upwardly through said opening for 125 130

said chamber, and electrical resistors for heating said gases.

7. A crematory furnace comprising a furnace chamber, an ash collecting trough in the floor of said chamber, an opening through said trough, a collecting tray therebelow, a plurality of electrical resisting rods, means for passing gases endwise toward the center of said rods, and a chamber through which said gases may flow to said retort 10 chamber.

Signed at Los Angeles, California, this 5 day of March, 1926.

LAWSON H. GIDDINGS.
